The ornamental design for an electric connector, as shown and described.

DESCRIPTION

FIG. 1 is a 1st perspective view of an electric connector, showing our new design;

FIG. 2 is a 2nd perspective view thereof;

FIG. 3 is a front elevation view thereof;

FIG. 4 is a rear elevation view thereof;

FIG. 5 is a top plan view thereof;

FIG. 6 is a bottom plan view thereof; and,

FIG. 7 is a left side view thereof, with the right side view being symmetrical to the left side view.

The shadings in the figures show contour and not surface ornamentation.
